UNITED STATES PATENT OFFICE

GEORGE E. EVANS, OF MONMOUTH, ILLINOIS.

WHEELED PLOW.

SPECIFICATION forming part of Letters Patent No. 620,575, dated March 7, 1899.

Application filed November 10, 1897. Serial No. 658,091. (No model.)

To all whom it may concern:

Be it known that I, GEORGE E. EVANS, a citizen of the United States, residing at Monmouth, in the county of Warren and State of Illinois, have invented certain new and useful improvements in Wheeled Plows, of which the following is a specification.

My invention relates to certain improvements in wheeled plows; and it consists in the new parts and new correlations and combinations of parts, hereinafter specifically pointed out and explained, for the general object of providing a more simple, convenient, and useful wheeled plow than has heretofore been constructed.

Referring to the drawings accompanying and forming a part of this specification, Figure 1 is a plan view of my wheel-plow. Fig. 2 is a land-side elevation of the same with the plow lowered. Fig. 3 is a furrow-side elevation of the same with the plow raised for transportation. Fig. 4 is a detailed view of the foot-lever raising and locking device with the plow lowered seen from the land side. Fig. 5 is the same with the plow raised. Fig. 6 is a detail view of the foot-lever raising and locking device with the plow lowered, seen from the furrow side with the link-bar broken away. Fig. 7 is the same, showing the position of the parts with the plow lowered. Figs. 8, 9, 10, and 11 are detail views of arm 58, arm 55, and foot-lever 59, respectively, which several parts are hereinafter specifically referred to.

In the drawings, 1 represents the main frame, consisting of flat steel parallel bars, connected by the arched bracket 1^a in front and sustaining between the two rear ends a caster-wheel bracket 2, which holds the sleeve 3, in which is journaled the vertical portion of the bent axle 4 of the caster-wheel 6. On the furrow side the main frame is supported by the furrow-wheel 5, journaled on the axle 7, which is bent upward, extends vertically for a convenient distance, and is then bent inward, forming at 8 an attachment for the pole-bracket P.

The vertical portion of the axle 7 is journaled in the sleeve formed in the bracket 9, rigidly attached to the frame. The furrow-

wheel is raised and lowered with reference to the frame by means of the lever 10, which at its forward end is linked by the bar 11 to the sleeve-bracket 9, while it bears at 12 upon the vertical bar 13, rigidly fixed to the vertical part of the axle by brackets 14, above and below the play of the sleeve. The lever 10 locks in place by the toothed segment 16 on the bar 13 engaging a spring-dog operated by a thumb-latch on the lever in the usual manner.

On the land side the frame is supported by the land-wheel 17, journaled on the axle 18. The rocking axle 16 extends transversely under the main frame, is journaled on hangers 20 beneath said frame, and extends beyond the landward side of the frame for a convenient distance.

The axle 19 may be locked in place by the rod 49 and the arm 48, attached to the furrowward end of the axle, as hereinafter described.

The axle 18 bears the web 21, terminating in the sleeve 22, journaled upon the axle 19. A washer 23 serves to keep the sleeve 22 in the proper position on the axle. The frame 75 is raised and lowered with reference to the land-wheel by means of the lever 24, rigidly affixed to the sleeve 22, whereby the sleeve is rotated on the axle 19, bringing the axle 18 either over or under the axle 19 or to any intermediate position.

The lever 24 is locked in place by means of the toothed segment 25, rigidly attached to the axle 19, and the usual spring-dog and thumb-latch.

From the upper end of the caster-wheel axle 4 extends furrowward the slotted arm 26, connected by the rod 27 with the inner extremity of the furrow-wheel axle 7. By this means the caster-wheel is caused to take a direction in turning the plow such as will bring the rear of the plow into the proper position in the smallest possible time and space.

Is a seat sustained by a curved spring standard s on the rear landward side of the frame. The plow proper consists of the share 28, moldboard 29, landside 30, and beam 31.

Draft-power is applied at the end of the beam, which is provided with the usual clevis-

bracket 32. The plow is suspended beneath the frame by means of two arched rock-shafts or "bails" 33 and 34. The weight of the plow is borne almost entirely by the rear bail 33, which is journaled in rearward extensions of the axle-hangers 20 at each end, and its central horizontal portion is journaled in the beam-bracket 35 on the rear downward-curving portion of the beam 31. The front bail 34 is journaled in suitable brackets 36 on the front part of the frame and its central portion is under the front part of the beam, working in the slotted bracket 37 thereon. The rear bail extends rearward from its frame-journals, is nearly the shape of a letter U, and its rear portion is so journaled on the plow-beam as to allow no play. The front bail, on the contrary, extends forward from its frame-journal and works in a slot, as stated, allowing play. This play is rendered necessary not only from the unequal lengths and angles of inclination to the beam of the two bails, but also from the fact that, as hereinafter described, both in raising and lowering the plow 25 the front bail operates to raise and lower the point before the rear bail comes into operation. The rear bail 33 bears on its leg on the furrow side an arm 38, disposed at right angles to the leg, to which is attached one end 30 of the strong coil-spring 39, pulling from the front curve of the frame, operating powerfully to raise the plow from the ground and tending to equalize its weight. The rear bail is also linked by the hoisting-link 40 (see Figs. 35 4 and 5) to the lower member of the hoisting-lever 41, which is fulcrumed at its central portion on the bracket 41^a on the furrow side of the frame and extends upward therefrom, having its upper member somewhat bent forward, as shown. The upper member is provided with a horizontal slot 42 midway its length and a hole 43 at its upper end. The second lever 44 is fulcrumed at the same point and revolves in a plane parallel to that 45 of the hoisting-lever 41 and operates it by means of the pin 45, working in the slot 42. On the inner side of the lever 44 is a connecting-rod 46, operating the front bail 34 by means of the arm 47 thereon near its furrow-side-frame journal.

The apparatus described forms an independent means of raising and lowering the plow, but not of locking it in either position. When the plow is down, it is raised by throwing the second lever 44 backward. That lever operates at once upon the front bail through the rod 46 and the arm 47, tipping the front of the bail, and thereby the point of the plow, upward; but it does not exert any lifting power on the rear bail till the pin 45 travels backward and through the length of the slot 42 and engages the hoisting-lever 41. The backward motion being then continued, the whole plow is raised and thrown forward. It is lowered by reversing the operation, the point being first tipped downward,

since the pin 45 has to travel again the length of the slot 42 before engaging the lever 41. By this means in raising the plow the point is invariably first tipped upward, which in itself causes the plow to run out of the ground within a few feet, while in lowering the plow the point is so depressed as to cause it to run into the ground to the required depth of itself, thus in practice utilizing the draft of the machine for both purposes. The furrowward end of the rocking axle 19 extends beyond the frame and bears the upward-extending arm 48. The rod 49, which is shown in the drawings as disposed along the side of the frame, may be raised and attached at its rear extremity to the upper end of the hoisting-lever 41 by inserting its inwardly-bent end into the hole 43. In that position it forms a connecting-link between the lever 41 and the arm 48 on the rocking axle 19, whereby said axle may be rocked, and the segment 25 and lever 24, with its spring-dog, forming a rigid connection with the axle 18, its web 21, and sleeve 22, such rocking of the axle 19 raises and lowers the frame with reference to the land-wheel 17 simultaneously with the raising and lowering of the plow from the ground. The coil-spring 49', attached at the rear to a bracket 50 on the rear of the frame and also 95 in front of the arm 48, tends to assist in raising the frame and plow when the rod 49 is attached to the lever 41. If it be not desired to make use of the rod 49 in the manner described, it may be disposed as shown, its inward-bent end engaging an ear of the bracket 50 and holding the axle 19 in a perfectly rigid position, when the frame can be raised and lowered with reference to the land-wheel by means of the lever 24, as already described. 105

I will now describe my foot-lever locking, raising, and lowering device whereby I provide means for locking the plow in a raised or lowered position and at the same time provide means for raising and lowering the plow 110 and actuating the levers independent of the use of hand-power upon the lever 44. This device will be best understood by reference to Figs 4, 5, 6, 7, and 8.

51 is a foot-lever fulcrumed on a hanger 52 115 on the landward side of the frame 1 and extending upward outside the frame having a pedal 53 on its upper end for the application of foot-power. The hanger 52 is located between the front-bail journal and the axle-hanger somewhat nearer the bail-journal. The foot-lever 51 is keyed to a short rock-shaft 54, journaled in said hanger, to which also is keyed the curved arm 55 inside the frame. The lever 51, the rock-shaft 54, and 120 the curved arm 55 form in reality but one bell-crank lever. The forward rotation of the foot-lever 51 is arrested by the stop 71 engaging the dog 56 on the lever 55. The lower end of the lever 55 is connected at the point 125 67 with the link 57, and thereby with the arm 58, which is loosely strung on the axle 19 and

held in place by means of the collar 59, which is rigidly attached by means of a set-screw. The lower rear edge of the arm 55 is carried backward beyond its pivot connection with the link 57, forming the shoulder 72.

60 is an arm rigidly attached to the horizontal landward end of the front bail near its journal-point and disposed so as to extend downward when the plow is lowered. It is connected by the link-bar 61 to the arm 58 at the same point at which the link 57 connects the curved arm 55 thereto—that is to say, the rear end link 57, the front end of the arm 58, and the rear end of the link-bar 61 are strung on the bolt 66 in the order named from left to right. The foot-lever 59 is strung on the same bolt between the arm 58 and the link-bar 61. The foot-lever 59 bears the inward-extending foot-rest or pedal 73 and an outward-extending lug 62. The lower edge of the lug 62 forms a face or shoulder 74, which corresponds in lateral position and is adapted to engage with a corresponding shoulder 75 on the forward lower edge of the arm 58 when the foot-lever 59 is thrown forward.

The lip 63 corresponds in lateral position with the curved arm 55, which has the shoulder 72 projecting upward and in contact with the lip 63 when the plow is lowered and in the position shown in Fig. 5 when the plow is raised. When the plow is lowered, it is locked into position by the foot-lever 51, raising the arm 55 into the position shown in Fig. 4, whereby the fulcrum of the lever 51, the link connection at 67, and the bolt 66 are in the same straight line. The link 57 and the curved arm 55 thus operate as a rigid bar to resist any forward pull of the link-bar 61, whereby the front bail 34 is locked in place, and thereby through the rod 46, the levers 44 and 41, and the rear bail 33 the plow is also locked into position. When the plow is to be raised, the foot-lever 59 is thrown forward, bringing its lip 63 down upon the shoulder 72 of the arm 55, bringing the point 67 down out of line with bolt 66 and fulcrum 54 and unlocking the plow, which can now be raised either by means of the lever 44, as already described, or by forcing forward the foot-lever 59 until its shoulder 74 is brought into contact with the corresponding shoulder 75 on the arm 58. In that position the lever 59 is practically a continuation of the arm 58, and pressure rocks that arm forward until it is in a horizontal position, as shown in Fig. 5. The forward motion of the arm 58 has actuated the front bail by means of the link-bar 61, that has produced precisely the same movement of the rod 46, levers 44 and 41, and rear bail 33 as hereinbefore described when the actuating force was applied by means of the lever 44. The plow being thus raised, the link-bar 61 and the link 56, having their three pivotal points in the same straight line, form, practically, a rigid bar, preventing any further motion of the front bail in either direction,

whereby the plow is locked in its raised position. It being desired to lower the plow, the foot-lever 51 is thrust forward, raising the bolt 66 from its "center" and allowing the plow to be lowered either by continued pressure upon the foot-lever 51 or by means of the handle 44, as before explained. Thus the plow can be raised and lowered by alternate pressure on the foot-levers, which are adapted to be operated by the left and right feet of the operator as he sits in the seat described and that independently of the lever 44.

In practice it will not be found necessary to make use of the hand-lever 44 except in exceptional cases, since the draft of the plow and the pull of the spring 39 so assist the operator that very slight foot-pressure suffices to throw the plow out of or into the ground.

When the plow is lowered, the foot-lever 59 can be dropped back out of the way of the driver, as shown in Fig. 4.

Having thus described my invention, what I claim as new, and desire to secure by Letters Patent, is—

1. In combination, the plow, the wheeled frame, the plow-beam, the front and rear bails, the lever and the link connections between said lever and the front and rear bail adapted to shift the front bail in advance of the rear bail when said lever is operated, substantially as described.

2. The combination of a plow, a wheeled frame carrying said plow on front and rear bails, a slotted lever pivoted on said frame linked to said rear bail and a second lever pivoted on said frame linked to said front bail and actuating said first lever by means of a pin working in said slot.

3. The combination of a plow, a wheeled frame bearing said plow on front and rear arched bails, a hoisting-lever fulcrumed on said frame, rocking said rear shaft, a second lever also fulcrumed on said frame rocking said forward shaft and actuating said hoisting-lever by means of a slot-and-pin connection between said levers.

4. The combination of a plow, a wheeled frame, a rear bail journaled in said frame at its extremities, extending backward and having its central arched portion journaled on the rear part of said plow-beam, a front bail also journaled on said frame at its extremities extending forward and having its central arched portion working in a slotted bracket on the front part of the plow-beam, said front bail bearing on its furrowward horizontal portion a crank-arm extending vertically upward when said bail is lowered, a lever linked to said arm fulcrumed on the frame and a lever linked to said rear bail fulcrumed on said frame, said levers revolving in parallel planes and a pin-and-slot connection between said levers.

5. In a wheel-plow, in combination rear and front bails, a hoisting-lever fulcrumed on the frame having its lower member connected

with said rear bail and its upper member horizontally slotted, an actuating-lever fulcrumed at the same point with the hoisting-lever and moving in a plane parallel to that 5 of the hoisting-lever bearing a pin working in the slot of said hoisting-lever and a link connection of said actuating-lever with said front bail.

6. The combination of a plow, a wheeled 10 frame, front and rear bails suspending said plow under the frame, link connection between said bails, a downwardly-extending arm attached to said front bail, a link-bar extending rearward from said arm, a bell- 15 crank foot-lever fulcrumed on said frame at its lower extremity connected by a link with said link-bar and both link and link-bar connected pivotally with a rearward-extending arm journaled on the frame, and a second 20 foot-lever fulcrumed on the pivotal connection of said link-bar, link and arm, as described.

7. The combination of a plow, suspended beneath a wheeled frame, by front and rear 25 bails, link connecting between said bails and means for rocking and locking said bails consisting of foot-levers 59' and 51 arm 58, link-bar 61, link 57, and arm 60.

8. In a wheel-plow, in combination a frame, 30 a plow suspended under said frame on front and rear bails, link connection between said bails and means for raising and locking said plow with reference to the frame comprising a vertical bell-crank foot-lever fulcrumed on 35 said frame, a link-bar actuating a crank-arm on said front bail, a forward-extending arm journaled on said frame, and a link connecting the lower end of said link-bar and the forward end of said forward-extending bar.

40 9. In a wheel-plow, in combination a frame, a plow suspended under said frame by front and rear bails, link connection between said bails a bell-crank foot-lever vertically fulcrumed on said frame having its lower rear 45 edge carried back forming a shoulder, a link-bar actuating a crank-arm on said forward arm-bail, a forward-extending arm journaled on said frame to the rear of the fulcrum of said bell-crank foot-lever having a projecting shoulder on its lower forward edge, a link attached to the lower end of said bell-crank foot-lever, a second foot-lever having a lateral lug on its lower portion bearing a downward-projecting lip, a bolt on which are 55 strung from landward furrowward in the order named, the link, the front end of the said forward-extending arm, the second foot-lever, and the rear end of the link-bar, as described.

60 10. The combination of a plow, suspended beneath a wheeled frame by front and rear bails journaled in the frame, a lever 41 fulcrumed on said frame linked to said rear bail, and bearing a slot 42, a lever 44 fulcrumed at 65 the same point with lever 41 swinging parallel to it and having a pin 45 working in the

slot 42, a rod 46 attached to an upward-extending crank-arm 47 on said front bail, a downward-extending crank-arm 60 on said front bail, a rearward-extending link-bar 61 70 attached to said crank-arm 60, a foot-lever 51, a rock-shaft 54, bearing a dog 56 adapted to engage the stop 71, a curved arm 55 forming with said rock-shaft 54 and lever 51 a bell-crank lever, a link 57, forward-extending arm 75 58 journaled on the frame, said arm 58, link 57 foot-lever 59 and link-bar 61 being strung on the bolt 66.

11. The combination of a plow, a frame supported by a rear caster-wheel, a furrow-wheel 80 and a land-wheel, said land-wheel having an axle rigidly connected to a second axle, extending transversely beneath the frame and being journaled in hangers beneath said frame, said second axle bearing a crank-arm 85 at its furrowward extremity, a lever on said sleeve locking to a toothed segment on said second axle, a rod connecting said crank of said second axle to a lever connected with bail suspending said plow beneath said frame 90 and means for actuating said bails whereby said plow is lifted out of the ground and said first axle is caused to rotate beneath and raise said second axle and thereby the frame, simultaneously. 95

12. The combination of a plow, a wheeled frame, a rearward-arched bail journaled in said frame carrying said plow, a forward-arching bail journaled in said frame having its central arched portion bearing under the 100 forward part of the plow-beam, a lever pivoted on said frame adapted to actuate said front bail, a second lever pivoted at the same point on the frame with said first-mentioned lever, said second lever having a lower member adapted to actuate said rearward-arching bail and an upper member having a horizontal slot, a pin attached to said first-mentioned lever, working in said slot and actuating said second lever, and means for locking said plow 110 in raised or lowered position.

13. The combination of a plow, a wheeled frame, a rearward-arching bail journaled on said frame carrying said plow, a frontward-arching bail journaled on said frame working 115 in a slot on the forward end of the plow-beam, a lever fulcrumed at its central portion on said frame having its lower member linked to said rear bail, a cranked rocking axle journaled in the frame carrying the land-wheel, 120 a crank-arm on said rocking axle, link connection of said crank-arm with the upper member of said lever, a second lever fulcrumed on the frame on the same line with said first lever, revolving in a plane parallel 125 to that of said first lever and connected therewith by a pin on said second lever moving in a slot on said first lever, link connection of said second lever with said frontward-arching bail a rearward-extending link-bar on said arm, a bell-cranted foot-lever vertically journaled on said frame, a link carried on the 130

lower extremity thereof, a forward-extending arm loosely strung on said rocking axle, a bolt on which are strung the rear extremities of said link and said link-bar and the forward extremity of the arm last aforesaid, a floating foot-lever also strung on said bolt having its lower portion widened into a lug and bearing a downward-extending lip, and being adapted in forward rotation to engage and form one lever with said forward-extending arm, as described
